UNITED STATES PATENT OFFICE.

GEORGE M. KNIGHT, OF ADRIAN, MICHIGAN.

GRATE-BAR.

SPECIFICATION forming part of Letters Patent No. 404,719, dated June 4, 1889.

Application filed September 26, 1888. Serial No. 286,473. (No model.)

To all whom it may concern:

Be it known that I, GEORGE M. KNIGHT, a citizen of the United States, residing at Adrian, in the county of Lenawee and State 5 of Michigan, have invented certain new and useful Improvements in Grate-Bars to be used under Boilers and in Furnaces, of which the following is a specification.

My invention relates to improvements in grates for furnaces of all kinds, more particularly, however, for steam-boiler furnaces; and it consists in certain novelties in the construction, arrangement, and combination of the various parts, all of which I will now 15 proceed to point out and describe, reference being had to the accompanying drawings, in which—

Figure 1 is a plan view of my apparatus with two of the grate-sections removed. Fig. 20 2 is a side elevation of the same, and Fig. 3 is an end elevation of one of the pipes with the grate in section.

Similar letters refer to similar parts throughout the several views.

25 In the above drawings, J represents a series of pipes which extend longitudinally underneath the grate-bars and are provided on one end with the removable caps I. The opposite ends of these pipes communicate with a 30 chamber G. At regular intervals and cast integral with the pipes J are the bearing-plates a. These bearing-plates are adapted to receive the ends of the grate-sections L and support the same, and are provided on their 35 upper surfaces with a small lug b, adapted to rise up between the bars of the grate-section, and thus hold the latter in place. The pipes J are provided on their upper surfaces between the bearing-plates with numerous ori- 40 fices or perforations d.

The operation of my apparatus will now be understood. The chamber G is connected with a fan for creating an air-current. Air is forced into the chamber G and from it

into the pipes J, which extend longitudinally 45 underneath and adjacent to the grate-sections. From the pipes it passes up through the orifices d, and is driven in sharp blasts up through the grate-sections against the bed of the fire. A constant and steady stream 50 of air is thus furnished along the entire length of the grate, keeping the grate-sections from burning out and insuring thorough combustion.

I am also enabled by the use of my apparatus to utilize the cheapest kinds of fuel—such as slack coal, screenings, and sawdust. The peculiar arrangement of the grate-sections adapts them for ready removal and replacing, should one burn out, without dis- 60 turbing the rest.

By providing each individual pipe with an end cap, and by removing the same, each pipe can be readily cleaned out, irrespective of the others, and consequently much more 65 thoroughly than if all had to be cleaned at the same time.

What I claim is—

1. A grate for a furnace, consisting of a series of pipes extending underneath and ad- 70 jacent to a series of grate-sections and pro- jected on their upper surfaces with perforations, of bearings on said pipes formed integral therewith for supporting said grate-sections, substantially as described.

2. The combination, in a furnace-grate, of the grate-sections L, pipes J, having perforations d, bearing-plates a, formed integral with said pipes and provided with lugs b, and a chamber G, into which said pipes extend and 80 from which a current of air is supplied to the pipes, substantially as described.

In testimony whereof I affix my signature in presence of two witnesses.

GEORGE M. KNIGHT.
